AUTOMOBILE MARKER LOCK

Joseph Richard Purvis, Toronto, Ontario, Canada, assignor of one-half to Henry James Hacker, Toronto, Ontario, Canada

Application February 9, 1939, Serial No. 255,397

7 Claims. (Cl. 40—125)

My invention relates to improvements in automobile marker locks of the type disclosed in my United States Patent No. 2,086,779 dated July 13, 1937, and in my Canadian Patent No. 371,955 dated February 15, 1938, and the object of the present invention is to simplify and cheapen the construction of the lock, to provide a lock in which none of the parts can become lost or which would be awkward to manipulate back into place, which will prevent the attempted insertion of the parts into place in the wrong position and it consists essentially in the arrangement and construction of parts hereinafter described.

Fig. 1 is a front view of a marker plate showing my lock applied thereto.

Fig. 2 is an enlarged sectional view through the marker plate showing my lock in elevation.

Fig. 3 is a sectional view on line 3—3 Fig. 5, showing the marker plate in the locked position.

Fig. 4 is a similar view to Fig. 3 showing the marker plate and the locking mechanism in position prior to locking.

Fig. 5 is a sectional view on line 5—5 Fig. 3.

Fig. 6 is a sectional view on line 6—6 Fig. 3.

Fig. 7 is a sectional view on line 7—7 Fig. 3.

Fig. 8 is a perspective detail of the slide piece forming the marker slot engaging member.

Fig. 9 is a perspective detail of the spring pressed latch plate engaging the slide piece to hold it in the locking position.

In the drawing like characters of reference indicate corresponding parts in each figure.

The marker plate 1 is provided with the usual slots 2 and 3 adjacent its upper edge, thereby leaving narrow portions 4 and 5 of the plate extending between the upper edge of each slot and plate.

The locking mechanisms 6 and 7 coact with the slots 2 and 3 and portions 4 and 5 to lock the plate 1 permanently in position.

Each locking mechanism is mounted on a vertical bar 8 secured to a carrying frame 9. The upper end of each bar 8 is provided with a head 8^x which is hook shaped as clearly seen in Figs. 3 and 4 and provided with side walls 10 and 11 in each of which is formed an open ended slot 12 in which the upper edge portion of the marker plate is inserted and a vertical groove 13 on its inner face.

The inner or long arm 9^x of the hook is provided in its inner face with a recess 14, the bottom of which is inclined as shown and with a transverse groove 15.

The short arm of the hook is formed with a

recess 16 on its inner face of its extreme end for a purpose which will hereafter appear.

A slide piece 17 is slidably mounted against the inner face of the bar 8 and fits between the side walls 10 and 11 of the head 8^x.

The main portion of the slide piece is in the form of a tongue extending from an enlarged lower end 18 and terminating at its upper end in a laterally extending latching rib 19.

The enlargement 18 is provided with a laterally projecting portion 20 which when the parts are in the locking position enters and fits the recess 16. (See Fig. 3.) The opposite side of the enlargement bears against the bar 8 and the lower portion of the enlargement depends to 15 form a bearing surface 18^x for the marker plate directly beneath the marker plate slot.

A latching plate 21 is provided with a turned end 22 freely fitting into the transverse groove 15 so as to pivot therein. The plate 21 is pressed outward by the spring 23 held in the recess 14 so as to hold the plate in an inclined position in the path of the rib 19 of the slide plate 17. Normally such rib bears against the lower edge of the plate 21 at the bottom of the incline. 25

In order to lock the marker plate in position the marker plate is applied to the slide pieces 17 so that the projections 20 pass through the slots 2 and 3 in the position shown in Fig. 4. The plate is then forced upward carrying the 30 outer face of each plate portion 4 and 5 into sliding contact with the inner face of the short arm of the hooked head 9 so as to slide upward thereagainst into the position shown in Fig. 3. Simultaneously with this movement the ribs 19 of 35 the mechanisms 6 and 7 are held by the plate portions 4 and 5 to travel parallel with the vertical faces of the hooked heads 9 to force the inclined plates inwardly against the pressure of the springs 23 so that the ribs 19 pass the upper 40 ends of the plates 21 allowing such upper ends to spring behind the ribs thereby locking the slide pieces and marker plate from downward movement.

In order to prevent the plates 21 and slide 45 pieces 17 becoming detached when in the unlocked position, I provide the plate 21 with upwardly curved side tongues 24 which enter the grooves 13 and extend longitudinally thereof and the slide piece 17 with laterally extending projections 25 which enter the grooves 13. The lower end of each side wall 11 is provided with downward extensions 26 which normally assume the position indicated by dotted lines in Fig. 5. 50

While the projections are in this position the 55

plate 21 and slide piece 17 are inserted. The ends of the projections 26 are then turned inward as indicated at 27 into the path of the projections 25 thereby effectually locking the slide piece from withdrawal.

5 In order to prevent the lower portion of the marker plate vibrating I curve the lower end of each bar 8 towards the plate and secure the plate thereto by means of bolts 21.

10 In order to remove the marker plate such plate would have to be destroyed by severing the portions 4 and 5 at the outer ends of the slots 2 and 3 and then bending the centre portion of the plate to make it bulge laterally so as to shorten the 15 distance between the aforesaid severed ends, which ends would then be pulled laterally out of the hooked portions of the bars, thus removing and at the same time spoiling the marker plate for further use.

15 20 What I claim as my invention is:

1. A marker lock comprising a vertical bar member having a hooked upper end into which the upper edge of a slotted marker plate is insertable, a slidable marker plate locking member movable 25 longitudinally of the aforesaid bar member from a lower position extending below the hook to an upper position substantially within the hook and extending outwardly therefrom to engage the slot of the insertable marker plate, and means coacting with that portion of the inserted marker plate which extends above the slot thereof for automatically securing the slidable member in the upper position.

2. In a marker lock, the combination with a 30 marker plate having a slot adjacent its upper edge, of a bar member extending at the back of the plate and having a hooked upper end into which the slotted upper edge of the plate extends, locking means interposed between the plate and the back arm of the hook and engaging the slot and adapted to be held in the locking position by that portion of the marker plate extending above the slot when interposed between the locking 35 mechanism and the front arm of the hook.

40 45 3. A marker lock comprising a vertical bar member having a hooked upper end into which the upper edge of a slotted marker plate is insertable, marker plate locking means interposed between the back arm of the hook and the inserted marker plate and adapted to extend through the marker plate slot and to be held in locking position by that portion of the marker plate extending above the aforesaid slot when interposed between locking mechanism and the front arm of the hook, and means for preventing 50 detachment of the locking mechanism from the bar when in the unlocked position.

4. In a marker lock, the combination with a 55 slotted marker plate, of a vertical bar member having a hooked upper end, a slide piece engaging

the back of the marker plate and slidable against the back arm of the hook, a spring pressed plate carried by the back arm of the hook and inclined upward and away from such back arm and means at the upper end of the slide piece with which the upper end of the spring plate engages when such slide piece end is carried past the upper end of the spring plate.

5 In a marker lock, the combination with the marker plate having a slot adjacent its upper edge, of a bar member extending at the back of the marker plate and having a hooked upper end into which the slotted upper edge of the plate extends, a wall at each side of the hooked member and formed integral therewith, a slide piece slidably bearing upon the inner face of the bar and having a projection engaging the slot of the marker plate, means engaging the upper end of the slide piece when slid upward for locking the slide piece from return movement, projections extending laterally from the slide piece and coacting stops carried by the side walls limiting the downward movement of the slide piece when released by the removal of the marker plate.

6. In a marker lock, the combination with the marker plate having a slot adjacent its upper edge, of a bar member extending at the back of the marker plate and having a hooked upper end into which the slotted upper edge of the marker plate extends, a wall at each side of the hooked member and formed integral therewith, a groove in the inner face of each wall, a spring pressed plate pivotally mounted between the side walls and extending laterally into the grooves of the walls, such lateral edge portions forming tongues 35 curved up from the spring plate, and a slide piece engaging the slot of the marker plate and adapted to be forced upward together with the marker plate into the aforesaid hook portion, and means at the upper end of the slide piece engaged by 40 the upper edge of the spring plate when the slide piece is forced upward as aforesaid to lock the slide piece and marker plate within the hooked portion of the bar member.

7. In a marker lock, the combination with the marker plate having a slot adjacent its upper edge, of a bar member extending at the back of the marker plate and having a hooked upper end into which the slotted upper edge of the marker plate extends, a wall at each side of the hooked member, a groove in the inner face of each wall, a slide plate engaging the slot of the marker plate and slidably engaging the grooves of the side walls and adapted to be forced upward together with the marker plate into the aforesaid hooked 50 end, and means for automatically locking the slide from withdrawal from the hooked end as the marker plate and slide piece are carried upward into the hook.
